UNITED STATES PATENT OFFICE.

WILLIAM F. BROWN, OF NEWARK, NEW JERSEY, ASSIGNOR TO THE BIGELOW CARPET COMPANY, OF NEW YORK, N. Y.

DESIGN FOR A CARPET.

SPECIFICATION forming part of Design No. 22,772, dated September 12, 1893.

Application filed August 1, 1893. Serial No. 482,120. Term of patent 3½ years.

To all whom it may concern:

Be it known that I, WILLIAM F. BROWN, a subject of the Queen of Great Britain, residing at Newark, in the county of Essex and State of New Jersey, United States of America, have invented and produced a new and original Design for a Carpet, of which the following is a specification, reference being had to the accompanying drawing, forming a part thereof, which represents a face view of a carpet in which the new design is embodied.

The invention relates to a design to be worked into or upon surfaces, such as carpets and similar fabrics, and it consists in the novel configuration and grouping of figures as herein shown and claimed.

The design consists of a body A and a border B. The body A consists of groupings of floral wreaths in conjunction with spiral figures and clusters of flowers. The border B consists of floral wreaths in festoon arrangement in conjunction with a floral festooned figure and floral and bar scrolls.

I claim—

1. In a design for a carpet the body A, substantially as shown.
2. In a design for a carpet the border B, substantially as shown.
3. The design for carpets, consisting of the body A and the border B, substantially as shown.

WILLIAM F. BROWN.
